BRUSH

Filed May 31, 1930

Inventor
Arthur C. Rounds
By Thomas A. Jenkins Jr.

Attorney

UNITED STATES PATENT OFFICE

ARTHUR C. ROUNDS, OF SCITUATE, RHODE ISLAND

BRUSH

Application filed May 31, 1930. Serial No. 457,706.

My invention relates to brushes, particularly brushes of the so-called reversible type described in Patent No. 573,198, issued Dec. 15, 1896, to B. F. Baxter. This type of brush consisted in a handle member hitherto made out of relatively cheap material, such as wood, which would tend to become worn in time and a head member having suitable brush means, such as bristles projecting from the lower end thereof. According to the Baxter patent his improvement in the art consisted in providing a concave surface on the lower surface of the handle member and a convex surface on the upper surface of the head member so that the brush can be readily reversed and when the parts were tightened together could be readily aligned. It was thus only necessary in Baxter, after the front bristles had become worn in use, to unloosen a threaded member and turn the brush around and thus any worn rear bristles would become the front bristles so the life of the brush head would be practically doubled.

I have found out in practice that the head members including the bristles thereof, had tended to wear out quite quickly in use and my present invention includes the idea of having a head member made of more or less permanent material and which may be made of ornamental material and of providing in connection with said ornamental handle member the usual head member which is intended to be replaceable. I thus provide a construction in which the head members may be readily replaced without going to the expense of buying an additional handle member and I have provided a handle member which may thus be made of relatively expensive ornamented material more beautiful than any produced hitherto. I thus with an initial, possibly somewhat greater first cost, am enabled to provide an ornamental brush of this type which is adapted to have the replaceable head members sold separately and replaced therein and thus have a brush, parts of which may be easily replaced at a relatively smaller cost than the cost of buying a new brush of the old type.

My invention is particularly adapted for use in so-called dust brushes of a well known

type, wherein the bristle portion thereof and overlapping handle portion comprise long narrow elongated members in order that the front end of the brush may get into narrow places to clean them out. It is obvious that in use the front part of the brush will tend to become much more worn than the rear part of the brush and hitherto it has usually been necessary when this has been the case to throw the entire brush away. An object of my invention therefore is to provide a dust brush of this type of pleasing appearance in which the brush member itself can be readily replaced as desired.

As will be apparent from the disclosure of the Baxter patent, brushes of this type have had a male member protruding upwardly through the handle member and an unsightly nut on the top of the handle member to secure the handle member to the head member. A further feature of my invention relates to the fact that I embed one of the attaching members in the lower surface only of the handle member so as to provide a handle member having an ornamental unbroken unapertured top surface more pleasing to the user and one which will not tend to tear or catch against the user's clothing or other objects. I believe I am therefore the first to realize that a brush of this description could be manufactured without one of the attaching members being visible at all on the upper surface of the handle member. In my preferred embodiment, I provide a female socket depending from the handle member, an aperture in the head member and screw means for securing the head member to the handle member. It is thus apparent that with this construction I am enabled to provide a type of attaching member wherein the screw means can be readily applied from underneath by means of the screw member without interference from the brush means or stiff bristles projecting downwardly from the head member.

These and such other objects of my invention as may hereinafter appear will be best understood from a description of embodiments thereof such as shown in the accompanying drawing.

In the drawing, Fig. 1 is a side elevation of a brush constructed in accordance with my invention.

Fig. 2 is a view similar to Fig. 1 with the head member and the head member attaching portion of the handle member being shown in longitudinal section.

Fig. 3 is a view generally similar to Fig. 2 showing the head member and screw attaching means in detached position.

Fig. 4 is a cross sectional view of my improved embodiment through the attaching means thereof.

Fig. 5 is a cross sectional view through the attaching means of a slightly different embodiment of my invention.

In the drawing, wherein like characters of reference indicate like parts throughout, 10 generally indicates a brush constructed according to the principles of my invention. Said brush includes the handle member 12. One feature of my invention relates to improvements in the handle member itself. Said handle member 12 is preferably shaped with 25 the handle forming end 14 and a front end 16 having a bottom surface 18 for attachment of the head member thereto. As stated, one feature of my invention consists in providing a handle member 12 of more beautiful appearance than any constructed hitherto, which may be made out of more or less permanent material such as bakelite, celluloid, metal, wood, etc., having an unapertured unbroken top surface 20. Said brush 10 includes in combination with the handle member 12, the head member 22 which is preferably constructed of relatively cheap material such as wood and which has the top surface 24 adapted to abut the bottom surface 18 of said handle member 40 and a bottom surface having brush means projecting downwardly therefrom. In my preferred embodiment, said brush means 26 comprises the bristles 26 embedded at desired intervals in the head member 22. In order 45 that said head member may be revolvable and replaceable relative to said handle member, I preferably form one of said contacting surfaces 18 or 24 of concave formation from one side to the other and the other convex from 50 one side to the other; in my preferred embodiment, the lower surface 18 of the handle 12 preferably is concave from side to side and the upper surface 24 of the head member 22 preferably convex from side to side.

55 I also provide suitable means to detachably secure said head member 22 to said handle member 12. For this purpose I provide an attaching member 28 in association with the lower portion of said handle member 12 and 60 an attaching member 30 in association with the head member 22, one of said members comprising a male member, the other of said members comprising a female member. In my preferred embodiment, the attaching member 28 is embedded in the lower portion of

said handle member 12 substantially centrally thereof. The head member is preferably provided with the aperture 32 having the counter-sunk socket 34 in the lower end thereof. The attaching member 30 is adapted to cooperate with said aperture 32 in said head member and said attaching member 28 in said handle member to secure said members together. In the preferred embodiment shown in Figs. 1-4, said attaching members are constructed as follows: The threaded socket member 28 is provided with a head 35 adapted to be suitably embedded in said handle member front end substantially centrally thereof. This may be done in any suitable manner, such as by counter-sinking it in the lower surface 18 of said handle member 12 after it has been made or by locating it in the mould while the bakelite or other composition material of the handle member is moulded and pressed around it. Said socket member 28 is provided with the integral threaded socket 36 projecting downwardly therefrom internally threaded as at 38 and in this instance the other attaching member functioning in association with the head member 22 comprises the screw 30 having the head 40 adapted to be embedded in said aperture socket 34 in said head member and the threaded end 42 thereof adapted to project through 90 said aperture 32 and into the threaded socket 38 of said handle member to detachably secure said members together. It is obvious, however, that the character of said attaching members 28 and 30 may be reversed, 100 thus in the embodiment shown in Fig. 5, the attaching member comprises the bolt 28' having the head 35' embedded in the handle member 12 and the threaded bolt end 28' projecting downwardly through the aperture 32 in 105 said head member and the other attaching member comprises the nut 30' internally threaded and adapted to be secured around the end of said bolt 28' within the socket 34 to detachably secure said members together. 110 I prefer the embodiment shown in Figs. 1-4 as it is relatively easier, if desired, with the medium of a screw driver, to thread the screw upwardly through the aperture 32 and into the threaded socket 38 between the bristles 26 than it is to spread the bristles apart and to thread the nut 40' on to the projecting bolt 28' from said handle member. 115

Where either of the embodiments are employed, however, in order to detach the head member 22 from said handle member 12, it is merely necessary to unscrew or otherwise detach the attaching member 30 adapted to function with the head member 22, when said head member 22 may be removed from said handle member 12. As also explained in the Baxter patent, if it is desired merely to twist the brush around so that the unworn rear portion of the bristles 26 in said head member may be switched around to become the front 130

portion, it is merely necessary to partially unscrew or detach the threaded member 30, when, as explained in detail in said Baxter patent, the brush may be switched around so 5 as to make the fresh rear end thereof the new front end thereof.

It is understood that my invention is not limited to the specific embodiments shown and that various deviations may be made 10 therefrom without departing from the spirit and scope of the appended claim.

What I claim is:

In a reversible ended dust brush, a permanent handle member having a handle-forming rear end and a narrow front end having an unapertured unbroken top surface and a bottom surface for attachment of the head member thereto and having an attaching member embedded therein and projecting 20 downwardly from the lower portion thereof

substantially centrally thereof, a replaceable cooperating narrow head member having an attaching socket substantially centrally thereof, a top surface adapted to abut the bottom surface of said handle member and a bottom surface having brush means projecting downwardly therefrom, one of said contacting surfaces being concaved and the outer convexed from one side to the other to rest one within the other and firmly retain the members from 75 relative lateral movement and an attaching member adapted to cooperate with said aperture in said head member and said attaching member in said handle member to secure said members together, one of said attaching members comprising a threaded male member and the other a threaded female member.

In testimony whereof I affix my signature.
